UNITED STATES PATENT OFFICE.

HENRY WILKE, OF SEATTLE, WASHINGTON.

ACCOUNT SYSTEM.

No. 901,507.

Specification of Letters Patent.

Patented Oct. 20, 1908.

Application filed March 30, 1908. Serial No. 424,268.

To all whom it may concern:

Be it known that I, HENRY WILKE, a citizen of the United States of America, and a resident of the city of Seattle, in the county 5 of King and State of Washington, have invented certain new and useful Improvements in Account Systems, of which the following is a specification.

My invention relates to improvements in 10 account systems wherein record cards or the like are employed.

The primary object of my invention is to facilitate identification of any desired card of a group or series.

15 With the above and other objects referred to hereinafter in view, the invention resides in certain novel and useful features set forth in the following description and defined in the appended claims.

20 With reference to the accompanying drawing, wherein like reference numerals designate similar parts throughout: Figure 1 is a face view of a record card embodying features of my invention, and, Fig. 2 is a view 25 in perspective illustrating the arrangement of such record cards in a system of account ing.

In the drawing reference numeral 1 designates a record card and 2 a guide card. 30 These cards are arranged substantially as illustrated in Fig. 2, where it is designed to associate a guide card with a particular group of record cards.

For convenience in Fig. 2 is illustrated ten 35 record cards in the first group, which are related to the guide card bearing the letter A, while but four record cards are indicated in the rear group relating to the guide card bearing the letter B. It will be obvious how 40 ever, that any number of groups of record cards may be employed, and that each group may comprise a suitable number of cards and have associated therewith a guide card.

In carrying out my invention I provide 45 the record card 1 of each group with top marginal projections as 3, which extend one beyond the other and have their outer end edges beveled, whereby portions 4 of the projections 3 appear in inclined relations above 50 the record cards. On these portions 4 the names of persons with whom accounts are kept are written in line with the inclined edges. Thus the names may be read more easily when desired to select from the group 55 a card pertaining to any particular account.

By slanting the end edges of the projec-

tions 3, as heretofore described, a comparatively long field for writing is afforded on each, which field may be further bounded by a line or mark as 7 extending parallel with 60 the beveled edge.

The marginal projections 3 are preferably provided with tabs 5, which are numbered consecutively in respective groups of cards, and the portions 4 likewise numbered, as 65 clearly shown in the drawing. On the projections 3 I may also provide an alphabetical and numerical index, as at 6, the letter designating the group to which the record card belongs and the number the position of 70 the card in its group.

While I have illustrated my invention applied to record cards such as are suitable for keeping accounts in a banking system it may be applied to cards for other analogous 75 uses:

As the full names of persons having accounts are recorded on the portions 4, it is obvious that the card bearing the desired account may be readily selected from the 80 group by the name it bears. This enables a bookkeeper unfamiliar with the numbers of the different accounts to rapidly operate the system.

Having thus described my invention, what 85 I claim as new and desire to secure by Letters Patent of the United States of America, is:

1. A group of record cards provided with marginal portions projecting one beyond the 90 other and having edges slanting outwardly from respective cards.

2. A group of record cards provided with marginal extensions projecting one beyond the other along the upper edges of the cards, 95 the projecting portions of said extensions having edges slanting outwardly from respective cards.

3. A group of record cards provided with marginal extensions projecting one beyond 100 the other and terminating in beveled end edges, each of said extensions having a guiding mark extending substantially parallel with its beveled edge, substantially as and for the purpose specified. 105

Signed at Seattle, Washington this 21 day of March 1908.

HENRY WILKE.
